WALTER VAN E. THOMPSON, OF LOS ANGELES, CALIFORNIA, ASSIGNOR TO THOMPSON MANUFACTURING COMPANY, OF LOS ANGELES, CALIFORNIA, A CORPORATION OF CALIFORNIA

QUICK COUPLER VALVE

Application filed October 6, 1928. Serial No. 310,795.

My invention relates to irrigation sprinklers, and relates particularly to the type of sprinkling system having a detachable sprinkler-unit which is above the ground level, and an underground portion having a permanent part to which the detachable sprinkler-unit may be attached. This type of irrigation system is used principally on playgrounds, golf courses, and the like, because when the sprinklers are not in use they may be removed and there will be no projections which will interfere with the use of the property. When it is desired to irrigate the property, the detachable sprinkler-unit may be attached to the permanent part of the underground portion.

This type of sprinkler is usually made so that the sprinkler-unit opens a valve in the underground portion when it is attached thereto. In the ordinary form of sprinkler system of this nature the sprinkler-unit is attached to the underground portion by a latch-means. The valve-opening means is so constructed that the valve is opened before the sprinkler-unit is entirely placed on the underground portion. This allows the water to leak, and it will spray onto the operator. A further disadvantage is that the area around the permanent portion is usually muddy because of the excess of irrigation.

It is one of the objects of my invention to provide a sprinkler system of this character in which the sprinkler-unit is connected to the permanent part before the valve is opened. This feature is advantageous inasmuch as it prevents leakage during the installing of the sprinkler-unit.

It is also an object of this invention to provide a sprinkler system in which the valve of the permanent part is closed before the sprinkler-unit is detached from the permanent part. This feature prevents a leakage during the removal of the sprinkler unit.

A still further object of my invention is to provide a sprinkler system in which the sprinkler-unit is screw-threadedly connected to the permanent part of the system. This feature provides a reliable connection between these parts so that a fluid-tight connection is assured, and so that there is no danger of the sprinkler-unit being inadvertently detached.

A still further object of the invention is to provide a sprinkler system of the character in which the permanent part has a water passage which is closed by a closure member, and in which the sprinkler-unit has a coupling portion which removes the closure from the end of the passage when the sprinkler-unit is installed. The coupling portion moves into the end of the passage as the closure is removed from the end of the passage. This feature of the invention prevents foreign matter from entering the permanent part, and furthermore provides for a tight closure for the permanent part when the sprinkler-unit is not installed.

A further object of the invention is to provide a sprinkler system of the character referred to in which the closure operates a valve of the permanent part, which valve closes the passage therethrough.

A further object of the invention is to provide a sprinkler system in which the closure is threadedly located in the end of the passage, and in which the sprinkler-unit has means for rotating the closure to advance it from the end of the passage, the coupling portion of the sprinkler-unit also being threaded and being advanced into the threaded end as the closure is advanced from the threaded end.

It is another object of the invention to provide a sprinkler system of the character specified, in which the valve of the permanent portion is adjustable relative to the closure, so that it may be opened different amounts when the sprinkler-unit is attached in order to permit different volumes of water to pass through the sprinkler-unit.

A still further object of the invention is to provide a sprinkling system of the character mentioned, in which the means for determining the amount that the valve is opened when the sprinkler-unit is installed in place may be adjusted while the sprinkler-unit is detached, and may be adjusted from the top of the permanent part without disassembling any of the parts.

It is a still further object of the invention to provide a sprinkler system in which the closure is engaged by the sprinkler-unit, and

moved from the end of the opening, and in which a coupling part of the sprinkler-unit simultaneously moves into the opening. After the coupling part of the sprinkler-unit is at least partly in the end of the passage the closure engages and opens the valve so that a flow of water occurs.

An object of the invention is to provide a sprinkler coupling which has but few parts and which is positive in operation.

10 An important part of the invention is that the valve is opened by means on the closure, but is closed by separate means such as a spring or water pressure.

15 Another important part of my invention is that the closure is provided with a seat which is clamped against the body of the permanent part of the device in order that leakage be prohibited.

20 In the preferred form of my invention the permanent part is provided with a passage having a threaded opening and a seat surrounding the opening. The closure has a threaded portion adapted to screw into the 25 threaded opening, and has a large portion adapted to tightly engage the seat. In the passage is valve means operable when said closure is operated.

25 I have briefly enumerated what I consider 30 to be the most important objects of the invention. In the following description other objects of the invention will be described, and the construction of the invention which embodies these objects will be pointed out in 35 detail.

In order that the invention may be readily understood by those skilled in the art I shall refer during the following description to the accompanying drawing in which,

40 Fig. 1 is an elevational view partly in section showing that part of a sprinkler system embodying the essentials of my invention. In this view the sprinkler-unit is shown in a position ready to be attached to the permanent part.

45 Figs. 2 and 3 are sectional views taken on the corresponding lines of Fig. 1.

50 Fig. 4 is an elevational section showing the sprinkler-unit fully attached to the permanent part.

55 Fig. 5 is a section taken on the line 5—5 of Fig. 4.

Fig. 6 is a view of a strainer plate of the invention.

60 I shall now describe in detail the parts shown in the drawing, which constitute my invention.

65 The sprinkler system includes underground header-piping 11 provided with T's, from which vertical supply-pipes 13 extend. To the upper end of each vertical supply-pipe 13 a permanent part 14 which embodies the features of the invention is secured.

70 I shall now describe in detail the construction of the permanent part 14 and the sprinkler-unit 15 which cooperates therewith.

75 Threadedly secured at 20 at the upper end of the supply-pipe 13 is a shell 21, the upper end 22 of which is located at or slightly below the level 23 of the ground. The shell 21 provides a water-passage 25. The upper end of the water-passage 25 is reduced in diameter, and is provided with a threaded end or threaded opening 26. The upper part of the water-passage 25 is provided with 80 four equi-spaced vertical guide-ribs 27 which are threaded on a larger diameter than the threaded end 26. The central part of the shell 21 has an annular removable partition-plate 28 which extends inwardly into the passage 25 and defines a cylindrical opening 29. The partition 28 is clamped between the parts 30 and 30^a which form the shell 21. The partition 28 constitutes a valve seat which is engaged by a valve 31, which will now be described. This valve 31 includes a member 32 provided with an annular channel which receives a gasket 33, this gasket 33 being adapted to engage the partition 28 for forming a fluid-tight seal.

85 Projecting upward inside the gasket 33 is a cylindrical wall 35 adapted to project through the cylindrical opening 29. The cylindrical wall 35 is provided with V-shaped notches 36 which act as a regulating means 90 for the valve. The lower portion of the part 32 is in the form of a cylindrical boss 37 having guide-ribs 38 which engage the lower part of the passage 25. Placed in the lower part of the passage against a shoulder 95 of the shell is a perforated plate 39. Between the plate 39 and the valve 31 is a spring 40 which tends to hold the valve in seated position.

100 The threaded end 26 of the shell 21 is adapted to be closed by a plug 42 which constitutes the closure of the invention. The closure 42 has a reduced end 43 which is threaded to screw into the threaded end 26; and has a large end 44 which is threaded to mesh 105 with the threads on the guide-ribs 27. Surrounding the inner end of the threaded end 26 is an annular seat 45, and carried by the upper part of the large end 44 of the closure 110 is a sealing gasket 46 capable of engaging the seat as shown in Fig. 1.

115 Formed through the closure 42 is a threaded opening 47 which is parallel to the axis of the passage 25. Threadedly secured in the opening 47 is a plunger 50 which is locked in place by a threaded plug 51. The lower end of the plunger 50 extends inside the cylindrical wall 35 and is adapted to engage an upper wall 52 of the valve member 32 for 120 removing the valve 31 from its seat. The upper end of the plunger 50 is provided with a diametral slot 53 so that the plunger 50 may be rotated and thus adjusted in position 125 relative to the closure 42. It will be seen 130

that the upper end of the plunger 50 is accessible from the top of the permanent part 14 when the plug 51 is removed. The plunger 50 constitutes the valve-opening means of the invention.

5 The sprinkler-unit 15 has a coupling-part 60 to which a vertical column-pipe 61 is threadedly secured. The upper end of the column-pipe 61 is provided with a rotating 10 sprinkler-head 62, which may be of any standard form. The coupling-part 60 is provided with handles 63 whereby it may be rotated. Projecting downward from the main portion of the coupling-part 60 is a 15 threaded-portion 64 provided with external threads 65 of the same diameter and pitch as the internal threads in the end 26 of the shell 21.

Supported in the lower part of a passage 20 66 formed through the coupling-part 60 is a diametral key 67, which projects downward from the lower part of the threaded-portion 64. This key 67 is adapted to extend into a key-slot 68 provided in the upper part of 25 the closure 42, as is illustrated in the drawing.

Threadedly secured at 70 to the coupling-part 60 is a guide-sleeve 71. The guide-sleeve 71 is cylindrical and is of such a diameter that it will receive the upper part of the 30 shell 21. The guide-sleeve 71 is adapted to hold the coupling-part 60 in alignment with the shell 21 so that the threaded-portion 65 will be in alignment with the threaded end 26 of the passage 25. At the upper part 35 of the threaded-portion 64 inside the guide-sleeve 70 is an annular packing-member 72 adapted to form a seal between the coupling part 60 and the upper end 22 of the shell 21 when the sprinkler-unit 15 is connected to the permanent-part 14 as illustrated in 40 Fig. 4.

In Fig. 1 of the drawing the parts of the permanent-part 14 are shown in the positions they occupy when the sprinkler-unit 15 is ready to be connected to the permanent-part. It will be seen that the valve 31 is tightly closed by the spring 40, and that the closure 42 closes the upper end of the passage 25. The gasket 46 is securely held against 45 the seat 45 so that the permanent-part is fluid-tight. All of the parts are at this time below the ground level 23 and will not interfere with any activities on the property. When it is desired to irrigate the property, 50 the sprinkler-unit 15 is attached to the permanent-part 14. The operation of attaching the parts will now be described.

The sprinkler-unit 15 is placed in such a 55 position that the key 67 extends into the key-slot 68 and the lower part of the guide-sleeve 71 extends around the upper part of the shell 21. The sprinkler-unit is thus shown in Fig. 1. The sprinkler-unit is then rotated by means of the handles 63 in such a direction 60 that the plug or closure 42 is screwed down-

ward from the threaded-end 26 of the shell 21. As the closure 42 advances downward the sprinkler-unit 15 moves downward therewith, and the threaded-portion 64 will be screwed into the threaded-end 26 of the passage 25. 70 The key 67 is made of a proper size so that the threads 65 of the threaded-portion 64 will properly enter the threaded end 26 of the passage 25.

The sprinkler-unit 15 is rotated until the 75 parts occupy the positions shown in Fig. 4. In Fig. 4 the threaded-portion 64 has completely entered the threaded end 26, and the annular gasket or sealing-means 72 is in sealing contact with the upper end 22 of the shell 80 21. There is absolutely no possibility of any leakage. The lower end of the plunger 50, by reason of this engagement with the wall 52, has moved the valve 31 from closed position as illustrated in Fig. 1, into open position as illustrated in Fig. 4. At this time the water will flow through the passage 25, as indicated by arrows 75, and into the sprinkler-unit 15, as indicated by arrows 76. The valve 31 is not opened until the threaded portion 64 has entered the threaded end 26. 85

The sprinkler-unit 15 is detached from the permanent-part 14 by rotating it in the opposite direction from which it is rotated to install it. When this rotation occurs the 90 threaded-portion 64 of the coupling-part 60 moves upward from the threaded end 26 of the passage 25. The pressure of the spring 40 against the valve member 32 causes the valve 31 to close. The valve comes against 95 its seat shortly after the closure 42 has entered the threaded opening 26. As rotation of the sprinkler-unit continues, the closure 42 and the parts connected thereto continue to move upward. When the closure member 100 42 arrives at closing position the gasket 46 thereof is clamped against the seat 45 of the shell 21, thus forming a fluid-tight seal. 105

The construction we have just described embodies all of the features of the invention 110 which were pointed out in the statement of invention of the application.

Briefly enumerated, the most important advantages of the invention are as follows:

During the attaching and detaching of the 115 sprinkler-unit 15, there is absolutely no leakage between the parts, in view of the fact that the valve 31 is not opened until after the threaded portion 64 has entered the threaded end 26, and in view of the fact that the valve 31 is closed before the threaded-portion 64 is entirely advanced from the threaded end 26.

Another advantage results from threaded- 120 ly connecting the sprinkler-unit 15 to the permanent-part 14. This threaded connection makes it possible to form a fluid-tight seal 125 and assures that the sprinkler-unit 15 will not become inadvertently detached from the permanent-part 14. 130

Another advantage of the invention results from the providing of the closure 42 which fills the threaded-end 26 when the sprinkler-unit 15 is detached from the permanent-part 14. This provision absolutely prevents any dirt or other foreign matter from entering the permanent-part 14, and obviates the possibility of any foreign matter interfering with the operation of the parts.

10 A further feature of the invention results from the provision of the adjustable plunger 50, which determines the time during the attaching of the sprinkler-unit 15 at which the valve 31 will be removed from its seat, 15 and determines the amount that the valve will be opened. By screwing the plunger 50 upward, the valve will be opened a smaller amount than is shown in Fig. 4, and by screwing the plunger 50 downward the valve will be opened a greater amount than is shown in Fig. 4.

Another advantage of the invention is that the plunger 50 is adjustable when the sprinkler-unit 15 is removed, without requiring the 20 dismantling of any of the parts of the permanent-part 14. As shown in the drawing, the upper end of the plunger 50 is accessible through the top of the opening 47 formed in the closure 42.

25 A very important advantage of the invention is that the closure 42 forms a fluid-tight seal when in the position shown in Fig. 1.

There are numerous other inherent and 30 obvious advantages of the invention, which I believe have been made manifest in the foregoing description.

I have described the invention as embodied 35 in a sprinkler system. The principle of the invention is not limited to this particular art, but may be embodied in construction of other arts where it is desired to have parts equivalent to the operative parts illustrated in this application. In view of the breadth of the invention, I desire to have the invention construed in the scope of the appended claims.

I claim as my invention:

1. In a device of the class described, the 40 combination of: a shell forming a passage, a valve adapted to close said passage; a closure adapted to close one end of said passage; a seat in said shell; an engaging means on said closure adapted to engage said seat and seal said end of said passage; means for removing said closure from closing position; and valve-opening means for unseating said valve when said closure is removed from closing position.

2. In a device of the class described, the 45 combination of: a shell forming a passage; a valve adapted to close said passage; a closure adapted to close one end of said passage; a seat in said shell; an engaging means on said closure adapted to engage said seat and seal said end of said passage; means for removing said closure from closing position;

and valve-opening means for unseating said valve when said closure is removed from closing position, said valve-opening means being adjustably supported in order that same may be adjusted in position for the purpose of unseating said valve different amounts.

3. In a device of the class described, the combination of: a shell forming a passage; a valve adapted to close said passage; a closure disposed within said passage; a seat in said shell; an engaging means on said closure adapted to engage said seat and seal one end of said passage; external means for removing said closure from closing position, said means having a projection adapted to move into the end of said passage to engage and unseat said closure; and valve-opening means for unseating said valve when said closure is removed from closing position, said valve-opening means being adjustably supported in order that same may be adjusted in position for the purpose of unseating said valve different amounts.

4. In a device of the class described, the combination of: a shell forming a passage, said passage having a screw-threaded end; a valve adapted to close said passage; a closure adapted to screw-thread into said screw-threaded end of said passage; a seat in said shell; an engaging means on said closure adapted to engage said seat and seal said end of said passage; means for rotating said closure so as to advance same from said screw-threaded end; and valve-opening means for unseating said valve when said closure is removed from closing position.

5. In a device of the class described, the combination of: a shell forming a passage, said passage having a screw-threaded end; a valve adapted to close said passage; a closure adapted to screw-thread into said screw-threaded end of said passage; a seat in said shell; an engaging means on said closure adapted to engage said seat and seal said end of said passage; means for rotating said closure so as to advance same from said screw-threaded end, said means having a threaded portion adapted to be screwed into said screw-threaded end of said passage as said closure is removed therefrom; and valve-opening means for unseating said valve when said closure is removed from closing position.

6. In a device of the class described, the combination of: a shell forming a passage, said passage having a screw-threaded end; a valve adapted to close said passage; a closure adapted to screw-thread into said screw-threaded end of said passage; a seat in said shell; an engaging means on said closure adapted to engage said seat and seal said end of said passage; means for rotating said closure so as to advance same from said screw-threaded end, said means having a threaded portion adapted to be screwed into said screw-

threaded end of said passage as said closure is removed therefrom; and valve-opening means for unseating said valve when said closure is removed from closing position, said valve-opening means being adjustably supported in order that same may be adjusted in position for the purpose of unseating said valve different amounts.

7. In a device of the class described, the combination of: a shell forming a passage, a portion of said passage being threaded, and forming a threaded-end, said threaded-end having threads of the same pitch as said threads in said passage; a closure having a reduced end and a large end, said ends of said closure having threads for meshing with said threads in said threaded end and said passage respectively, said closure being removable from a position in which said reduced end closes said threaded end, into a position in which said reduced end opens said threaded end; operating means for operating said closure; a seat in said shell; an engaging means on said closure adapted to engage said seat when said closure is in a position to fully close said threaded end; and valve means in said passage operated by said closure.

8. In a device of the class described, the combination of: a shell forming a passage, a portion of said passage being threaded, and forming a threaded-end, said threaded-end having threads of the same pitch as said threads in said passage; a closure having a reduced end and a large end, said ends of said closure having threads for meshing with said threads in said threaded-end and said passage respectively, said closure being movable from a position in which said reduced end closes said threaded-end, into a position in which said reduced end opens said threaded-end; operating means for operating said closure; a seat in said shell; an engaging means on said closure adapted to engage said seat when said closure is in a position to fully close said threaded-end; a valve seat in said passage; a valve adapted to engage said valve seat; seating means for said valve; and valve-opening means whereby said closure opens said valve.

9. In a device of the class described, the combination of: a shell forming a passage, a portion of said passage being threaded, and forming a threaded-end, said threaded-end having threads of the same pitch as said threads in said passage; a closure having a reduced end and a large end, said ends of said closure having threads for meshing with said threads in said threaded-end and said passage respectively, said closure being movable from a position in which said reduced end closes said threaded-end, into a position in which said reduced end opens said threaded end; operating means for operating said closure; a seat in said shell; an engaging means on said closure adapted to engage said seat when said closure is in a position to fully

close said threaded-end; a valve seat in said passage; a valve adapted to engage said valve seat; a yieldable seating means for seating said valve; and valve-opening means whereby said closure opens said valve.

70

10. In a quick coupler device, the combination of: a primary part adapted to be connected to a supply means; a valve guide removably connected to the upper end of said primary part; valve means seatable against said valve guide and retained thereby in said primary part; a secondary part secured to said primary part and having a closure means; and operating means whereby said valve means is operated subsequent to said closure means.

11. In a quick coupler device, the combination of: a primary part adapted to be connected to a supply means; a valve guide removably connected to the upper end of said primary part; a valve member seatable against said valve guide and retained thereby in said primary part; a plate in said primary part; a spring compressed between said valve member and said plate; a secondary part secured to said primary part and having a closure means; and operating means whereby said valve member is operated subsequent to said closure means.

In testimony whereof, I have hereunto set my hand at Los Angeles, California, this 29th day of September, 1928.

WALTER VAN E. THOMPSON.
